Patented Apr. 1, 1919.

UNITED STATES PATENT OFFICE.

MILFRED L. GREENSTREET AND SILVANUS F. LUMM, OF LEBANON, MISSOURI,
ASSIGNORS TO G. L. TIME SWITCH COMPANY, OF LEBANON, MISSOURI, A CO-
PARTNERSHIP.

INTERMITTENT TRAIN MECHANISM.

1,299,328.

Specification of Letters Patent.

Patented Apr. 1, 1919.

Application filed May 28, 1917. Serial No. 171,418.

To all whom it may concern:

Be it known that we, MILFRED L. GREENSTREET and SILVANUS F. LUMM, citizens of the United States, residing at the city of 5 Lebanon, county of Laclede, and State of Missouri, have invented a certain new and useful Improvement in Intermittent Train Mechanism, of which the following is a full, clear, and exact description, such as will 10 enable others skilled in the art to which it appertains to make and use the same, reference being had to the accompanying drawings, forming part of this specification.

This invention relates to certain improvements 15 in intermittent train mechanism, the operation of which is controlled from a clock mechanism, for the purpose of turning on or off an electric switch at predetermined times.

20 The broad object of our invention is to provide certain improvements in mechanisms of this type, the nature of which is such as to permit the use of standardized commercial clock movements of a well 25 known type in the device, and thus decrease to a considerable extent the cost of manufacture of the device. At the same time, it is the object of our invention to provide a greatly simplified mechanism of the sort described, in which all of the operating parts 30 are well protected by the clock casing, yet easily accessible for the purpose of setting the tripping mechanism.

The use of time switches is familiar in 35 the art, and our various improvements, as hereinafter described, permit our supplying an accurate, thoroughly practical, and entirely "fool-proof" device at a price which makes it available to anyone who may have 40 use for such apparatus. By the utilization of our improvements, our process of manufacture is greatly simplified, as we may purchase ordinary wall clocks of the type commercially designated the Waterbury move- 45 ment, fully assembled, with the clock casing, and by adding our improvements, may convert the striking train into a switch-operating train without requiring a disassembling and reassembling of the movements.

50 In the accompanying drawings, Figure 1 represents a partial front elevation of a clock frame equipped with our improvements, and showing also a portion of the clock dial;

55 Fig. 2 is a sectional elevation showing portions of the switch-operating train;

Fig. 3 is a partial side elevation, with casting parts in section, showing various portions of the switch-operating train.

Referring to these illustrations in detail by means of the reference numerals applied, 60 let it be understood that 1 designates generally the casing in which the movement is inclosed, only a portion thereof being shown, and 2 designates the clock dial which serves to cover and protect the movement. 65

Mounted within the casing and back of the dial is the customary frame 4 which, our invention presupposes, is of some conventional type such as the Waterbury movement shown. Within this frame are mounted the 70 customary time train and the train which in ordinary practice is utilized in operating the striking mechanism of the clock. The time train includes the minute hand shaft 5 and the hour hand sleeve 6 disposed on the front 75 of the frame and projecting through the dial 2, as is customary, so as to support on the exterior thereof the hour and minute hands. The minute hand shaft carries a pinion 7 and the hour hand sleeve carries a 80 pinion 8, which two pinions are connected by a reducing train made up of the conjoined pinions 9 and 10, the former meshing with the pinion 7 and the latter with the pinion 8. This is the conventional construction. 85

The switch-operating train includes the spring shaft 11 controlled by pawl and ratchet mechanism 12 in the customary fashion, and carrying the spring 14. The spring 90 shaft 11 carries also the spring wheel 15. The movement of the spring wheel 15 in the unwinding direction is controlled by the customary governing mechanism, which includes the spur gears 16, 17 and 18, and lantern gears carried by the latter, and the governor fan 19. 95

All of the parts thus far described are conventional parts of the clock mechanism. Our invention resides in the improvement in the 100 means for predetermining and controlling the operation of the switch-operating train from the time mechanism. It will be understood that the minute hand shaft 5 is operated by the time train in the conventional 105 fashion, and the hour hand sleeve 6 is operated from the shaft 5 through the pinions 7, 8, 9 and 10. Mounted on the front of the frame 4 is a staff 20 which, at its outer extremity carries the setting device revolvably 110

mounted thereon. This setting device includes the conjoined setting dial 21, and spur wheel 26, and a pair of tripping arms 22, the latter being arranged for rotation on the hub of said spur wheels 26 and the outer ends of said arms having frictional engagement with the setting dial, as hereinafter more fully described. The arrangement of this dial 21 is such that, when assembled 5 with the rest of the device, it occupies the same plane as does the clock dial 2, and the conventional movement may be adapted to accommodate it by simply punching out from the clock dial a hole of the proper diameter, which is slightly more than the diameter of the setting dial. The visible face of the setting dial 21 is divided on a diameter into two portions, each of which is calibrated into twelve subdivisions representing 10 the hours of a half day. The arms 22 are independently revolvable on the setting device and their length exceeds the radius of the dial 21 and their outer extremities are turned over the periphery of the dial and 15 down in front of the visible face thereof, where they are shaped to form indicators 24. The arms 22 have a spring tendency which operates to hold them in frictional engagement with the rear surface of the dial 21, 20 which frictional engagement operates to retain the arms 22 against revolution relative to the dial by casual influences. The turned-over extremities of the arms 22, however, are so arranged that there is a sufficient distance 25 between the indicators 24 and the opposite portions of the arms 22 to permit the latter to be disengaged from the rear surface of the dial, by pressure applied to the members 24. By operating the arms 22 in 30 this fashion, they may readily be set by hand to any of the selective positions about the dial 21. Each of the arms 22 carries a rearwardly projecting tripping lug 25. The relative size of pinions 26 and 10 is such 35 that the former is given one revolution upon every twenty-four hour movement of the time mechanism.

The detent mechanism for the switch-operating train includes the tripping staff 27 40 and the detent staff 28, both rotatably mounted in the frame. The latter staff carries a counting arm 29 which is adapted to co-operate with the toothed periphery of the spring wheel 15, in which, at predetermined 45 intervals, are formed the deep notches 15^a. The staff 28 also carries the rocking arm 30 which is disposed to co-operate with a cam 31 carried on the staff of the pinion 17. In the third place, the staff 28 carries the holding 50 arm 32 which is disposed to co-operate with a stud 34 carried on the spur wheel 18. The tripping staff 27 carries a restraining arm 35, which is arranged for co-operation with the stud 34, but which normally is out of 55 the path thereof. Staff 27 carries also the

lifting arm 36 which has a forwardly directed portion 36^a crossing the path of and in co-operation with counting arm 29, and a laterally turned tripping arm 36^b. The length of the arms 36^a and 36^b is such that 70 the latter occupies a position between the dial member 21 and the wheel 26 and in the path of the tripping lugs 25.

The parts are normally held in the position illustrated in Fig. 2 by the springs 38 75 and 39 of the staffs 28 and 27 respectively. During the operation of the time train, the arms 22 are revolved past the tripping arm 36^b, so that the lugs 25 successively are brought into contact therewith, and, by the 80 movement of said lugs 25 on rotation of wheel 26, tripping arm 36^b will be cammed upwardly so as to rock staff 28 against the influence of its spring, and lift counting arm 29 out of the slot 15^a, by virtue of the engagement of lifting arm 36^a therewith, and lift holding arm 32 out of engagement with stud 34 and place restraining arm 35 in the path of said stud. The train being thus 85 released, it will move until stopped by stud 90 34 coming up against arm 35 and this will carry the deep notch 15^a out from under the nose of counting arm 29. Upon continued rotation of wheel 26 from the time train, the tripping lug 25 in engagement with tripping arm 36^b will be moved past said arm, permitting it to drop under the influence of spring 39 which will remove restraining arm 35 out of the path of stud 34. The train will 95 then operate, and arm 30 will swing downward a short distance as its free end moves into a notch or low portion on the edge of cam 31 thereby rocking counting arm 29 into and out of engagement with the periphery of spring wheel 15. This movement will 100 continue to the point where the next deep notch 15^a is brought under counting arm 29 which, when it falls thereinto, will bring holding arm 32 down into the path of stud 34, catching the stud and stopping 105 the operation of the train. During such operation of the train, the switch may be turned on or off, movement being transmitted to the switch from the spring wheel 15 by any suitable gearing including a transmission pinion 40. 110

It will be seen that this arrangement provides a very effective and economical switch-operating mechanism in which a conventional clock movement of commercial type 115 120 may be utilized by the addition of a few simple and easily assembled parts. Furthermore, the arrangement of the setting dial to co-operate with the clock dial in the manner described forms a protection for the working parts and also produces a very slight instrument. This arrangement is secured by virtue of the arrangement of the tripping arms 22 and of the lifting arm 36. The setting of the tripping mechanism so as to trip 125 130

the switch-operating train at a predetermined time, is readily accomplished by applying pressure to the indicator 24 and then rotating the arm to the desired position. It 5 is of great advantage that, in this operation, it is unnecessary to open the movement or to utilize any implement which, in the hands of an unskilled person might work injury to the device.

10 We are aware that the device is susceptible of various changes and modifications, departing in particulars from the illustrative form herein shown, but comprehended nevertheless within the scope of the appended 15 claim.

What we claim is:

In a time controlled mechanism, the combination of a frame, a spring-actuated shaft mounted therein, a wheel on said shaft, a 20 rocking staff, a counting arm carried by said staff and arranged to engage said wheel, a tripping staff mounted in the frame, a lifting arm carried by said tripping staff and having a portion adapted to engage the counting 25 arm and a tripping portion extending exterior of the frame, a dial forming a covering

for said parts, said dial being provided with an opening, a rotatably mounted setting dial positioned within said opening, means for rotating said setting dial, a pair of independently operable setting arms mounted for rotation with said setting dial, each arm being disposed behind said dial and having a frictional contact with the rear face thereof under spring tendency whereby each arm 35 will retain its adjusted position upon the dial, the extremity of each arm being bent about the periphery of the dial and over a portion of the front surface thereof to form a manipulative indicator whereby the arm 40 may be moved rearwardly from the dial to permit its adjustment, the front surface of the setting dial being provided with indicia disposed in operative association with the indicators, and a tripping lug on each arm for 45 engaging the tripping portion of the lifting arm to lift the counting arm upon suitable rotation of the setting dial.

In testimony whereof we hereunto affix our signatures this 17th day of May, 1917. 50

MILFRED L. GREENSTREET.

SILVANUS F. LUMM.
